UNITED STATES PATENT OFFICE.

ARTHUR MILES, OF KANSAS CITY, MISSOURI.

MEANS FOR REPAIRING TUBES.

Application filed August 13, 1920. Serial No. 403,816.

To all whom it may concern:

Be it known that I, ARTHUR MILES, a subject of the King of Great Britain, residing at Kansas City, in the county of Jackson and State of Missouri, have invented certain new and useful Improvements in Means for Repairing Tubes; and I do declare the following to be a full, clear, and exact description of the invention, such as will enable others skilled in the art to which it appertains to make and use the same, reference being had to the accompanying drawings, and to the letters and figures of reference marked thereon, which form a part of this specification:

This invention relates to a method of and apparatus for repairing tubes and it is particularly applicable in connection with radiator tubes for motor vehicles.

It is well known that the tubes of radiators not infrequently split and on account of the peculiar construction of the arrangement of tubes and the fins or webs connecting them, considerable difficulty has heretofore been encountered in repairing them due to the inaccessibility of the tubes.

I have provided a novel method and mechanism for expeditiously effecting the repairs in the event that there is a leak in the radiator tube due to splitting or from any other cause. The mechanism for carrying out the method is illustrated in the accompanying drawings, in which—

Fig. 1 is a view partly in elevation and partly in section of a radiator, showing the manner of repairing the tubes.

Fig. 2 is a vertical, longitudinal, sectional view through a tube, showing the method of effecting the first step in the repair.

Fig. 3 is a similar view showing the second step.

Fig. 4 is a fragmentary view of a tube, an expanding packer and an expander, and

Fig. 5 is a fragmentary view of the bottom of a radiator, showing the closer for the bottom in place.

Assuming that the tubes 1 and 2 of the radiator 3 split and leak and it is desired to effect a repair, the bottom manifold 4 is cut out to provide an opening 5 which may later be closed by a closer or seal to be referred to hereinafter. After the opening 5 is made below the tubes to be repaired, a tubular patch 6 is introduced into the tube or tubes to be repaired through the opening 5. The tubular patch is provided with heads 7 and

7' approximately the diameter of the inner diameter of the tube to be repaired, for example, the tube 1. The heads 7 and 7' however, are of such diameter that the patch 60 may be freely moved into the tube 1.

The expanders 8 and 9 are then introduced into the tube 1 and they have sleeved thereon expanding packers 10 and 11, which are adapted to abut against the heads 6 and 7. 65 The expanders 8 and 9 are slightly conical and telescoped within the tubular patch 6 so that when they are drawn one toward the other, they will expand the packers 10 and 11 against the inner wall of the tube 1 to 70 seal off the portion of the tube 1 between the packers but permit the water to pass through the tubular patch 6.

In order to draw the expanders 8 and 9 one toward the other, I utilize a draw rod 75 or member 12 (see Fig. 2). The draw rod is provided with a hook or eye 13 adapted to engage the bend 14 of the expander-engaging member 15. The expander-engaging member 15 is substantially V-shaped with outwardly projecting ends 16 and 17 adapted to abut against the end of one of the expanders as, for example, 8. The draw member 12 extends down through the tube 1 and through the opening 5 and is provided with a threaded end 18, which is adapted to be engaged by a thumb nut 19 to force a tubular member 20 against the head of the expander 9.

The tubular member 20 may be sleeved on the draw member 12 and I prefer to apply a plate or disk 21 on the threaded end thereof which bears against the end of the tubular member 20 and which serves as an abutment for the jam nut 19. Therefore, when the nut 19 is screwed upon the threads, the member 20 will be moved longitudinally toward the member 15 and the member 15 and its expander 8 will be drawn toward the member 9, therefore, the two glands or expanders 8 and 9 will be forced into the tubular patch 6, drawing the packers 10 and 11 against the heads 7 and 7', causing them to expand and sealing off the tube 1 at these respective points. Since the patch 6 is tubular, however, the water may pass through it although the effective port area of the tube 1 will be restricted throughout the length of the patch.

After the glands or expanders 8 and 9 are 110 drawn tightly against the packers 10 and 11 to expand them, it becomes necessary to

remove the member 15. I, therefore, find it expedient to remove the jam or thumb nut 19, take off the disk or plate 21 and remove the tubular member 20. Then a tube 22 of smaller diameter will be introduced through the gland or expander 9, the tubular member 22 being long enough to extend up to and surround the member 15. Since the member 15 is of spring material and V-shaped, it will be apparent that after the tube 22 is forced thereon, the ends 16 and 17 retract from engagement with the head of the expander 8; that is, the ends 16 and 17 will be drawn together so as to release themselves from engagement with the head of the member 8, and since the distance between the ends 16 and 17 will be less than the diameter of the gland or expander 8, it is obvious that they may be withdrawn by pulling upon the draw member 12, leaving the patch in place, as shown in the tube 2 of Fig. 1. The repair to the tube has then been completed.

It then becomes necessary to close the previously made opening 5 in the manifold 4. The opening 5 is preferably elliptical and in order to close the same, I provide an elliptical plate 23, which may be inserted through the opening, as shown in dotted lines in Fig. 5, and then turned, shown in full lines of Fig. 5, to overlap the opening. The closer 23 may be faced with a packing of rubber or similar material 24 and at the center of the member 23, I prefer to provide a rivet head 25, upon which may be sleeved a clamp plate 26 to abut against the lower face of the manifold 4. Then the edge 27 of the rivet may be peened over or flanged so as to rivet the members 24 and 26 together, effectually sealing the opening 5. The completion of the repair to the radiator has now been accomplished.

It will be apparent from the foregoing that radiator tubes may be expeditiously and efficiently repaired without breaking the fins or otherwise distorting the radiator.

In actual practice I prefer to assemble the patch 6 with the expanders 8 and 9 carrying

the packers 10 and 11 outside of the tube; then place the member 15 in place with the attached draw member 12, apply the tube 20, plate 21 and nut 19, and then introduce the whole assembly into the tube. It will then be only necessary to turn the nut 19 in order to draw the expanders 8 and 9 into the tube and expand the packers 10 and 11, whereupon the nut 19 may be removed, the members 20 and 21 taken off and the member 22 inserted in order to release the member 15, accomplishing the desired result very quickly.

While I have specifically referred to the method as applied to radiator tubes, it is obvious that it may be practiced in repairing other types of tubes susceptible of such application.

What I claim and desire to secure by Letters-Patent is:

1. Means for repairing radiator tubes comprising a tubular patch, expanders in telescoping relation with said tube, expansible packers between the tube, and expanders, means for telescoping the expanders within the tube, and means for releasing the last named means. 75

2. Means for repairing leaky radiator tubes comprising a tubular patch, expansible packers at the ends of the tube, expanders therefor, means for actuating said expanders comprising a normally expanded expander-engaging member, and means for contracting the expander-engaging member to release it from engagement with the expander. 80

3. Means for repairing radiator tubes comprising a tubular patch, expanders in telescopic relation with the tubular patch, expansible packing rings between the tubular patch and the expanders, means for drawing the expanders within the tube, and means for releasing the drawing means whereby unimpeded through passageways will be provided through the tubular patch and through the expanders at the ends thereof. 85

In testimony whereof I affix my signature.

ARTHUR MILES.
